J. H. WANDVE

TROLLING SPOON

Filed Nov. 29, 1921

Inventor
John H. Wandve

UNITED STATES PATENT OFFICE.

JOHN H. WANDVE, OF KETCHIKAN, TERRITORY OF ALASKA.

TROLLING SPOON.

Application filed November 29, 1921. Serial No. 518,525.

To all whom it may concern:

Be it known that I, JOHN H. WANDVE, citizen of the United States, residing at Ketchikan, in the Territory of Alaska, have 5 invented certain new and useful Improvements in a Trolling Spoon, of which the following is a specification.

This invention relates to trolling spoons and more particularly to an improved spoon 10 for effecting a rapid rolling motion of the spoon while it is in use so that the opposite sides of the spoon will be rapidly exposed in succession.

Another object of the invention is to so 15 construct the spoon as to effect a rapidly rolling motion in connection with an appearance of flashing light produced by certain serrations and corrugations formed in the surface of the curved portions of the spoon.

20 Other objects of the invention will appear upon consideration of the following detail description and accompanying drawings, wherein:—

Figure 1 is a perspective view of the spoon 25 constructed in accordance with my invention,

Figure 2 is a longitudinal section through the same,

Figure 3 is a cross section on the line 3—3 30 of Fig. 2.

Referring to the drawings by numerals, the spoon consists of an elongated plate pointed at each end, the central portion 1 being straight and flat, the end portion 2 being curved upwardly and pointed at its 35 end at which point an opening 3 is provided to connect the hook 4. The curved top end 2 is slightly cup-shaped as will be indicated in Fig. 2 of the drawing and this cup shaped 40 curved surface is provided with diverging corrugations 5 presenting angular surfaces which will effect a varying rays of light flashes by virtue of the light changing from one angular surface to another when the 45 troll spoon is being drawn through the water. The opposite end 6 of the spoon 1 is curved in the opposite direction to that of the curved end 2 and is also provided with a swivel connection 7 whereby the line may 50 be connected. The curved end 6 is slightly less in width than the end 5 and is curved downwardly as distinguished from the up-

wardly curved end 2 and is provided with the corrugations which present the angular surfaces in the same manner as at the opposite 55 end.

In addition to the corrugations, cut or circular shaped depressions 8 and 9 are provided, one being pressed inwardly and the other outwardly in the opposite direction, the depression 9 at the end 2 being pressed outwardly in the said direction as the outwardly pressed curve of the end 2, while the depression 8 is pressed outwardly in the direction of the outwardly pressed curve 65 of the end 6. These depressions form irregular surfaces on the plate which in addition to the angular surfaces provided by the corrugations will cause a series of light flashes to occur when the troll is being drawn 70 through the water and since the troll is curved and shaped in the manner described it will have a rapidly rolling motion to effectively attract the fish toward the spoon.

Minor changes may be made in the detail 75 of construction without departing from the spirit of the invention or the scope of the claim hereunto appended.

What is claimed is:—

A trolling spoon of the character described comprising an elongated plate having its central intermediate portion straight, the ends of said plate being pointed and curved in opposite directions, each of said curved ends being provided with diverging 85 corrugations extending from the terminals of the central straight portion, a cupshaped depression formed in the straight portion at the base of the corrugations at each curved end, said cupshaped depressions being 90 formed in opposite directions so that the cupshaped depressions will cooperate with the corrugated ends to give the spoon a rolling motion and to give a series of flashing 95 lights during turning of same, and said spoon having a hook connected on one end and means for connecting the opposite curved end of the spoon to a line.

In testimony whereof I have affixed my signature in the presence of two witnesses.

JOHN H. WANDVE.
